UNITED STATES PATENT OFFICE.

JOHN H. RICHARDSON, OF MELROSE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR TRIMMING SOLES.

1,392,799.

Specification of Letters Patent.

Patented Oct. 4, 1921.

Application filed November 3, 1916. Serial No. 129,304.

To all whom it may concern:

Be it known that I, JOHN H. RICHARDSON, a citizen of the United States, residing at Melrose, in the county of Middlesex and 5 State of Massachusetts, have invented certain Improvements in Machines for Trimming Soles, of which the following description, in connection with the accompanying drawings, is a specification, like reference 10 characters on the drawings indicating like parts in the several figures.

This invention relates to trimming machines, and in particular to machines used to 15 perform the operation known as "jointing" in the manufacture of shoes. This operation consists in trimming the edge of the shank of a shoe from the point where the usual machine trimming operation is stopped to the heel breast.

20 One type of machine used for the performance of this operation includes a knife arranged to move along the shank edge to raise a shaving, and a second knife, moving substantially at right angles to the shank 25 edge to detach the shaving, the two knives being so coördinated that they reach alternately the same extreme point of movement. By the operation of this machine the shaving detached is cut up into small pieces, a procedure which wastes power, dulls the detaching or "chopping" knife rapidly, and entails more or less injury to the shank edge 30 in front of the heel breast, since a slight inaccuracy in adjustment of the chopping 35 knife will cause it to cut too deeply and make a series of scars along the shank.

It is a principal object of my invention to 40 obviate these difficulties by controlling the operation of the detaching means so that it will come into operative relation to the work only when desired. The power wasted in cutting the trimmed shaving into small 45 pieces is thereby saved, the rapid dulling and consequent frequent grinding and wear of the chopping knife is avoided, and the extreme care in adjustment formerly required are made unnecessary since a single cut in the shank edge at the heel breast does not damage the appearance of the shoe and 50 is not particularly objectionable.

A feature of my invention comprises a novel organization of trimming means for a sole edge, means for detaching the material trimmed, and means for controlling

the operation of the detaching means. The 55 detaching means need not, therefore, occupy operative position relatively to the work until the trimming means has reached the heel breast, and the difficulties incident to premature and repeated detaching operations are 60 avoided.

Another feature of the invention comprises manually operated means for controlling the operation of the detaching means by initiating its operation upon the work only 65 when necessary.

A further feature comprises a continuously driven detaching means normally held away from the work, and means for moving it to a potential operating position in relation to the work.

Another feature of the invention comprises a positively operated means for detaching a shaving raised on a sole edge, and mechanism for controlling its operation. 75 The detaching of the shaving is the result of positive detaching action, and the detaching means may be placed in actual operation on the work at the will of the operator.

Another feature comprises a detaching 80 means having two motions, one of which is effected positively through power-driven connections to detach the material trimmed, and the other of which is effected manually to shift the work-engaging instrumentality 85 from an idling field to its field of operation.

These and other features of the invention, comprising certain arrangements and combinations of parts will be best understood from the following description of a preferred embodiment of the invention selected 90 for purposes of illustration and shown in the drawings, in which—

Figure 1 is a side elevation of the head of the machine;

Fig. 2 is a plan; and

Fig. 3 is a front elevation.

The main frame 10 has bolted to it the head 12. The main drive shaft 14, rotated by any preferred means, extends from the 100 main frame, projects through the head, and carries an eccentric wrist pin 16 at its front end. A long stud 18 is fixedly mounted in the head by means of the set screw 20, and extends forward horizontally parallel to the 105 drive shaft. Mounted upon this stud is a sleeve 22, having at its rear end a downwardly extending yoke 24, which embraces

the wrist pin 16 by means of some approved bearing device, such as a block 26, sliding in the yoke and rotatably mounted on the wrist pin 16. The yoke has a number of stiffening 5 ribs 28, and an upwardly projecting lug 30, which bears against a hardened block 32 mounted in the head and holds the sleeve 22 in position on the stud 18.

The sleeve 22 has mounted on its forward 10 end a head 34 which carries the trimming knife 36. This knife is mounted in a horizontally extending dovetailed slot 38 in the lower part of the head, the rear wall of the dovetailed slot being deeply grooved as at 15 40 in order to permit the screw 42 to clamp the knife 36 firmly in place. It will be observed that the knife 36 has a cutting edge at each end, the right hand edge, as seen in Fig. 3, operating upon the right hand edge 20 of the shank of a shoe and the left hand edge operating upon the left hand edge of the shank when the shoe is turned over, as will be readily understood. The rotation of the shaft 14 and the wrist pin 16 causes oscillation 25 of the sleeve 22 and the head 34 carried by it and causes the knife 36 to vibrate back and forth along the edge of the shank.

The head 34 also carries a vertically extending dovetailed rib 44. Closely fitted to 30 slide freely upon this dovetailed rib is a correspondingly shaped slide 46 which has projecting horizontally from its front face a pin 48. Two upstanding brackets 50 and 52 on the rear and front ends of the head 12 35 respectively carry a rock shaft 54 having projecting crank arms 56 and 58. The crank arm 56 is engaged by a treadle rod 60 operated by a treadle not shown. A lateral extension on the crank arm 56 is engaged by 40 a compression spring 62 extending downward to the head, which tends to hold the crank arm in its uppermost position, and a vertically adjustable stop pin 64 adapted to engage the head is mounted in the extension 45 to limit its downward motion when the treadle is operated.

The upward movement of the crank arm 56 is limited in any desired way, as for instance by a stop above the treadle. The 50 crank arm 58 has a slot 66 at its outer end and a pivoted latch 68 is spring held downwardly over the end of the crank arm 58 to close the slot. A suspension link 70, having a yoke at its upper end in which is 55 mounted a pin 72, and a split bearing 74 at its lower end, extends between the pin 48 and the crank arm 58. The split bearing is properly fitted to the pin and the yoke embraces the crank arm, the pin 72 being removably held in the slot 66 by the latch 68. It will be clear that the slide 46 will oscillate with the head 34 owing to the dovetail connection between the two, and that at the 60 same time it can be moved up and down on the head 34 by the spring 62 and the treadle 65

rod 60, respectively, owing to the sliding feature of this connection.

The slide 46 carries two laterally extending arms 76, to the ends of which are pivoted two curved levers 78, 80, each of which carries at its lower end a split clamp in which is mounted the upwardly extending shank of a chopping knife 82. The chopping knives 82 have their cutting edges so shaped as to fit the cross section of the shank 75 of the style of shoe being operated upon. The upper ends of these levers carry rotatably adjustable eccentric pins 84 on which are mounted friction rollers 86. Fixedly mounted upon the head 12 is a guide block 80 88 having two slots 90 in its front face in which the rollers 86 are arranged to slide. The oscillation of the slide 46 will cause a corresponding oscillation of the pivots 79 of the levers and the confinement of the upper 85 ends of the levers to the slots 90 by means of the friction rollers 86 will cause an up-and-down chopping motion of the knives 82. The adjustment of the shanks of the knives 82 in the levers 78, 80 and of the eccentric 90 pins 84 at the upper ends of these levers will be such as to cause the cutting edges of the knife 36 and of the corresponding knives 82 to have, respectively, the same extreme 95 points of travel, the two coöoperating knives in each case reaching their common position alternately. The slots 90 are so directed that the underhanging ends of the levers and the knives they carry will have a substantially radial movement as regards the center of 100 oscillation of the head 34, while the trimming knife has a circular movement as regards this center. The shaving raised by the trimming knife will thus be cut square 105 across by the detaching knife, and the shoulder formed, if any, will be perpendicular to the shank edge.

Adjustably clamped to the forward end of the head 12 are two downwardly extending uprights 92 having pivotally clamped 110 at their lower ends the gages 94. These gages are conveniently bent in any desired manner and may be adjusted through the two screws 93, 95 to bring their lower ends into the proper position for engagement 115 with the heel breast of the shoe being operated upon. A frame 96 is mounted upon a slide 98 which engages a backwardly extending rib 100 upon the lower side of the forward end of the head 12 and is clamped 120 to the head by the screw 102. This frame carries at its forward end the downwardly extending rand guide 104 which is vertically adjustable by means of the clamp 106, the two adjustments 106 and 98 permitting the 125 adjustment of the guide in any desired position.

The operator will present the shoe to the machine with the upper toward him, the guide 104 being inserted properly in the 130

- crease between the upper and the shank, so that the proper cutting edge of the knife 36 will engage the shank at the point where the trimming was discontinued, and will 5 then move the shoe to the left as shown in Fig. 3, trimming the remainder of the shank. The spring 62 normally holds the rock shaft 54 in its extreme counter-clockwise position, thus holding the slide 46 raised in its upper- 10 most position with the knives 82 substantially lifted above the edge of the shoe sole being operated upon. These chopping knives 82 will oscillate above the shank edge without operating, and they will not come 15 in contact with the shank during this part of the operation. The shoe will be moved to the left until the right hand gage 94 comes in contact with the heel breast, this gage having been so adjusted that the end of the 20 path of movement of the knife 36 will then be exactly at the junction of the heel breast and the shank. The operator will then step on the treadle, pulling down the treadle rod 60, compressing the spring 62 and turning 25 the rock shaft 54 clockwise as seen in Fig. 3, until the pin 64 contacts the frame of the machine. This movement of the rock shaft will lower the slide 46 and cause the right hand knife to shift its operative path to op- 30 erate in consequence of shifting its range of action until the extreme lower point of its movement is identical with the extreme right hand point of movement of the knife 36, that is, at the junction of the heel breast and 35 shank. The knife 82 will then detach the shaving which the knife 36 has split from the shank, the operator will release the treadle, the slide 46 carrying the knives 82 will be restored to its uppermost position 40 by the spring 62, and the operator will remove the shoe from the machine, turn it over and apply the left side of the shank to the left hand cutting edge of the knife 36 in the same way, operating the treadle as 45 before, when the heel breast has reached the left hand breast gage 94 to control the operation of the corresponding chopping knife by bringing it into operative relation to the sole edge. 50 The holding of the chopping knives 82 away from the shank edge during the trimming operation avoids all danger of scarring the shank by the knives while the shaving is being raised. The smoothness of the shaving 55 operation is not impaired as formerly when the chopping knives were permitted to chop the sole edge repeatedly during the shaving operation. A further advantage of my invention resides in the fact that less 60 power is consumed than under former practice since the shaving is detached by one chopping operation instead of being cut to small pieces while the operation proceeds, as has been the case in previous machines 65 of this type. The duty on the chopping knives themselves is also much lighter since they make only one cut through the shaving, and the expense due to grinding and consequent wear is much smaller. It will be observed also that the chopping knives are 70 oscillated continuously whether in or out of operative position with respect to the shank edge so that there is no jar on the machine incidental to initiating their operation. 75
- It will also be found that the great care in adjustment of the detaching knives heretofore necessary may be dispensed with, since a slight cut in the shank at its junction with the heel breast will not be regarded as a blemish. 80
- What I claim as new and desire to secure by United States Letters Patent is:—
1. In a machine of the class described, means for trimming the sole of a shoe, 85 driven means including a cutter for detaching the material trimmed, and means actuatable during the operation of the machine for changing the path of the cutter without interrupting its motion. 90
  2. In a machine of the class described, means for trimming the sole of a shoe, driven means including a reciprocated cutter for detaching the material trimmed, and means for shifting the cutter from one field 95 of motion to another. 95
  3. In a machine of the class described, means for trimming the sole of a shoe, and means for detaching the trimmed material, constructed and arranged to be moved into 100 and out of its operative path relative to the sole. 100
  4. In a machine of the class described, means for trimming a sole, means for detaching the material trimmed normally held 105 out of operative relation to the work, mechanism for moving said detaching means into operative relation with the work, and means for operating said detaching means independently of the movement of the latter to 110 and from said relation. 110
  5. In a machine of the class described, means for trimming a sole, means for detaching the material trimmed in coöperative relation with said trimming means, but 115 normally held out of operative relation to the work, and constructed and arranged to be movable into such operative relation, and a stop stationary during the detaching operation limiting such movement at a point 120 insuring proper coöperative relation of said trimming and detaching means. 120
  6. In a machine of the class described, means for trimming a sole, a work-engaging element for detaching the material trimmed, 125 said element being movable manually from an inoperative portion to a working position relatively to the work, and driven mechanism arranged to impart operating movement to said element. 130

7. In a machine of the class described, means for trimming a sole, driven means including a work-engaging element for detaching the material trimmed, means arranged to move said element out of operative relation to the work, and manually operative means arranged to move said element into operative relation to the work.

8. In a machine of the class described, a knife constructed and arranged to trim along the edge of a shoe sole, and mechanism for giving said knife rapid oscillatory movements, a second knife normally inoperative as regards the work but arranged to cut transversely into the sole edge, and manually operated mechanism arranged to move said second knife into the work.

9. In a machine of the class described, means for trimming a sole-edge, a cutter, continuously driven means for operating the cutter, and manually controlled means for causing the cutter to detach the material trimmed by the first said means.

10. In a machine of the class described, means for trimming a sole, driven means arranged to occupy a coöperative relation to said trimming means for detaching the material trimmed, and manually operated mechanism arranged to change the relation of said trimming means and said detaching means while the latter is being driven.

11. In a machine of the class described, means for trimming a sole-edge, driven mechanism including a knife to which cutting motion is imparted positively, and controlling means arranged to cause the knife to detach the material trimmed by the first said means.

12. In a machine of the character described, means arranged to trim the edge of a shoe sole, a cutter, means arranged to move said cutter into operative relation with the work, and driven means arranged to operate said cutter to detach the material trimmed by said trimming means.

13. In a machine of the class described, means for trimming the sole of a shoe, means for detaching the material trimmed, and driving mechanism for said means constructed and arranged to operate it normally in a path out of operative relation to the work and to carry it into such operative relation when desired.

14. In a machine of the class described, means for trimming the edge of a shoe sole, means for detaching the trimmed material, and driving mechanism for said detaching means, relative to which said means is adjustable during the trimming of a sole.

15. In a machine of the class described, means for trimming the edge of a shoe sole, means for detaching the trimmed material from the sole, and driving mechanism for said latter means having positive connection

therewith in the direction of drive, but loose connection therewith in another direction, whereby said means may be moved into and out of operative relation to the work.

16. In a machine of the class described, means for trimming the edge of a shoe sole, means for detaching the material trimmed and an oscillatory drive member for said detaching means, relative to the center of oscillation of which said detaching means is movable.

17. In a machine of the class described, a sole trimming instrumentality, a rocking member, a chopping knife holder mounted on said member and adjustable toward and from the center of oscillation thereof, to control its operative relation to the work, and means for coöordinating said instrumentality and a knife carried by said holder to trim and detach a shaving from a shoe sole.

18. In a machine of the class described, means for trimming the sole of a shoe, means for detaching the material trimmed from the right side of the sole, means for detaching the material trimmed from the left side of the sole, and a member carrying said two detaching means and constructed and arranged to control their relation to the work.

19. In a machine of the class described, means for trimming the edge of a shoe sole, means for detaching the trimmed material from the sole, said latter means being continuously driven, but normally held in inoperative position with relation to the work, and mechanism for placing said means in operative relation to the work.

20. In a machine of the class described, means for trimming the edge of a shoe sole, and continuously driven means for detaching the trimmed material from the sole, constructed and arranged to remain normally out of operative relation to the work and to be placed in such operative relation at the will of the operator.

21. In a machine of the class described, means for trimming the edge of a shoe sole, means for detaching the material trimmed from the right and left sides of the sole, and continuously operating drive mechanism for said latter means, having connection therewith constructed and arranged to permit movement of said detaching means as a whole toward and away from the work.

22. In a machine of the class described, means for trimming the edge of a shoe sole, means for detaching the trimmed material from the sole, and continuously operating drive mechanism for said latter means, having connection therewith constructed and arranged to permit movement of said means as a whole into and out of operative relation with the work.

23. In a machine of the class described, means for trimming a shoe sole, an oscillating drive member, a slide on said member carrying means for detaching the trimmed material, and means for moving said slide relative to said member during the trimming of a sole for controlling the detaching means. 5
24. In a machine of the class described, 10 a sole trimming instrumentality, a power driven member, a chopping knife holder pivotally and slidably mounted on said member, a stationary member having a guideway formed in it, and a member adjustable on said holder positioned in said guideway for coördinating a knife carried by said holder with said trimming instrumentality. 15
25. In a machine of the class described, 20 means for trimming the sole of a shoe, movable means adjustable to coöperate therewith to detach the material trimmed, and means for controlling the path of movement of the detaching means without affecting the 25 coöperative adjustment between said trimming means and said detaching means. 30
26. In a machine of the class described, means for trimming the sole of a shoe, movable means for detaching the material 35 trimmed and means for changing the limits of movement of the latter means to bring it into or out of operative relation to the sole. 40
27. In a machine of the character described, means for trimming the sole of a shoe, driven means arranged to sever the material trimmed by said trimming means, and means arranged to shift the range of movement of said severing means. 45
28. In a machine of the character described, means for trimming the sole of a shoe, severing means movable to and from an operative relation to the work, and means arranged to impart severing motion 50 to said severing means independently of movement of the latter to and from operative relation as aforesaid. 55
29. In a machine of the character described, means for trimming the sole of a shoe, means for severing the material trimmed by said trimming means, means arranged to operate said severing means, and means for moving said severing means to and from operative relation to the work independently of the movement imparted to the severing means by said operating means. 60
30. In a machine of the character described, means arranged to shave the edge of a shoe sole, a cutter arranged to chop the shaving formed by said means, and means arranged to be operated manually to move said cutter in the direction of its chopping motion. 65
31. In a machine of the character described, means arranged to trim the edge of a shoe sole, a cutter arranged to detach the material trimmed by said trimming means, manually operative means arranged to move said cutter in the direction of its cutting movement, and driven means arranged to move said cutter in said direction. 70
32. In a machine of the character described, means arranged to trim the edge of a shoe-sole, a cutter arranged to detach the material trimmed by said trimming means, driven means arranged to move the cutter in the direction of its cutting motion, and means arranged to advance the limit of motion of the cutter in said direction as imparted by said driven means. 75
33. A machine of the character described comprising a chopping knife, and mechanism constructed and arranged to operate said knife, said mechanism including a reciprocatory member by which the chopping knife is supported but relatively to which the knife moves to execute its chopping motion, said supporting member being adjustable to advance and retract the chopping knife with respect to its lines of chopping motion. 80
34. A machine of the character described comprising a chopping knife, and mechanism for operating said knife, said mechanism including a movable carrier by which said knife is supported and to which it is pivotally connected so as to provide for relative angular movement, said carrier having oscillatory motion to impart chopping motion to the knife and being otherwise movable to shift the knife to different fields of motion. 90
35. In a machine of the class described, the combination with means for trimming the edge of a shoe-sole in front of and up to the line of the heel-breast, of a stop arranged to engage the breast of the heel of the shoe to limit the operation of said trimming means along the sole-edge, said stop and trimming means being relatively adjustable in a direction substantially perpendicular to the path of the trimming means. 100
36. In a machine of the class described, the combination with means for trimming the edge of a shoe-sole in front of and up to the line of the heel-breast, of a stop arranged to engage the breast of the heel of the shoe to limit the operation of said trimming means along the sole-edge, said stop and trimming means being relatively adjustable in directions substantially perpendicular and parallel to the path of the trimming means. 110

In testimony whereof I have signed my name to this specification.

JOHN H. RICHARDSON.

It is hereby certified that in Letters Patent No. 1,392,799, granted October 4, 1921, upon the application of John H. Richardson, of Melrose, Massachusetts, for an improvement in "Machines for Trimming Soles," errors appear in the printed specification requiring correction as follows: Page 3, line 29, strike out the words "to shift its operative path"; same page lines 87 and 88, claim 1, for the word "actuable" read *actuatable*, and line 127, claim 6, for the word "portion" read *position*; and that the said Letters Patent should be read with these corrections therein that the same may conform to the record of the case in the Patent Office.

Signed and sealed this 13th day of December, A. D., 1921.

[SEAL.]

KARL FENNING,
Acting Commissioner of Patents.
